APPARATUS FOR DEVELOPING PHOTOGRAPHIC FILMS

Hinsdale Smith, Jr., New York, N. Y.

Application March 1, 1938, Serial No. 193,223

5 Claims. (Cl. 95—90)

This device relates to a new and improved apparatus for developing photographic films and particularly so-called photographic cut films and films from film packs.

5 Films used in film packs present particular difficulties in developing and fixing. This is true because each image is fixed on an individual light sensitive film. The films, as used in photography, generally have a piece of substantially 10 light impervious paper covering the photosensitive emulsion on one side of the film. The other side of the film usually has a light absorbing substance thereon which prevents reflection of rays passing through the film, thus avoiding 15 halation. These films are generally put up in packs of twelve. Thus, when images have been received on each film, twelve individual films must be developed.

In placing these films in a developing bath 20 they must be handled in a dark room. Also, in transferring to a fixing bath they must not be exposed to light. Tanks have been devised into which the films may be placed and the developing, fixing and washing carried on there without 25 any transfer. However, these tanks have generally been large and the cut film holder therein difficult to load in the dark. Others have been easier to load, but could not have the developing solution removed and replaced by a fixed and 30 subsequently by a washer except in a dark room. Moreover such cut film holders and tanks have not permitted sufficient circulation of the various liquors to permit rapid developing of the film and removal of the light absorbing coating on 35 the back of the film. Furthermore, the cut film holders and tanks have been difficult to load without scratching the film. The cut film holders previously used to accommodate the films have been large and cumbersome necessitating 40 the waste of a large portion of the developing and fixing bath.

The present invention overcomes these difficulties by providing a cut film holder which is compact and may be adjusted for different sizes 45 of films.

In addition, the cut film holder on which the films are placed for development is so constructed that it may be readily loaded in the dark.

50 Another feature of this invention is that the cut film holder is so constructed that only the edges of the film, where there is no image, can contact any parts thereof thus avoiding the possibility of scratching the films.

55 Furthermore, the cut film holder is so con-

structed that the various liquors may freely circulate thereabout and therethrough and readily contact all parts of the film where needed.

Various other features and advantages of the invention will be apparent from the following 5 particular description and from an inspection of the accompanying drawings.

While reference in the specification and claims may be made to developing films it is to be understood that this shall embrace and include developing, fixing and washing as generally understood in the art to prepare a photographic negative for printing.

Although the novel features which are believed to be characteristic of this invention will be 15 particularly pointed out in the claims appended hereto, the invention itself, as to its objects and advantages, and the manner in which it may be carried out, may be better understood by referring to the following description taken in 20 connection with the accompanying drawings forming a part thereof, in which:

Fig. 1 is an elevational view of a cut film holder formed in accordance with the invention, the cut film holder being shown in association 25 with a developing tank, the tank being shown in vertical cross-section;

Fig. 2 is a horizontal section through the cut film holder taken along the line 2—2 of Fig. 1;

Fig. 3 is an enlarged fragmentary cross-section 30 taken through the cut film holder on the line 3—3 of Fig. 2;

Fig. 4 is a fragmentary top plan view of the cut film holder;

Fig. 5 is an enlarged fragmentary horizontal 35 sectional view through the cut film holder and illustrating particularly the cooperation between a film and the guide portions of the cut film holder; and

Fig. 6 is a fragmentary vertical sectional view 40 through the cut film holder illustrating the cooperation between the entering edge of the film and the guide portions of the cut film holder, taken along line 6—6 of Fig. 5.

Referring now to the drawings, 1 represents 45 generally the cut film holder which is adapted to hold films for developing, fixing and washing. This cut film holder may comprise end plates 2 and 9 connected by desirable means such as a plurality of posts 6 and 26. The end plate 2 50 has spiral channel guides 3 thereon and may have holes 4 therein to facilitate circulation of the developing, fixing and washing liquor, or any of them. This plate may have a central opening 5 therein which in addition to aiding in the cir- 55

culation of the various liquors may be used as a journal for an axle which may be passed through the reel. Secured to the plate 2 may be a plurality of posts 6 and 26 of a desired length which 5 may have affixed thereto intermediate their ends additional spiral guide members 7 secured thereto as at 8 and 28 respectively.

The posts 6 and 26 are preferably adapted to be releasably held by the plate 9 which has on 10 its under face spiral channel guide members 10 which are preferably in juxtaposition with the spiral channel guide members 3 on the plate 2. This plate 9 may also be provided with holes 11 corresponding to the small holes in the plate 2 15 which permit free circulation and may also have a central opening 12 therein for the same purposes as the opening 5 in the plate 2.

The posts 6 and 26 may pass respectively through openings 13 and 33 in the plate 9 and 20 the portions 18 of posts 6 which pass through the plate 9 may be held by means such as the adjustable ring 14 provided with cam surfaces 17 which abut against one or more of the portions 18 of the posts 6 which project above the 25 plate 9.

The adjustable ring 14 may be rotatably mounted on the plate 9 and releasably held by screws 15 passing through slots 16 in the adjustable ring 14. The screws 15 preferably have 30 enlarged heads 20 overlying the slots 16 so that they will bear against the adjustable ring 14. Thus it may be seen that by releasing the screws 15, the ring 14 may be rotated so that it does not hold the top portions 18 of the posts 6 and 35 the plate 9 can be adjusted to take varying widths of film. Conversely by rotating the adjustable ring in the opposite direction the cam surfaces 17 may be brought to bear against the portions 18 of the posts 6 and the plate 9 is thus 40 held in proper spaced relation to the plate 2.

The spiral guides 3 and 10 may be projected from any desired point but they should preferably emanate from circles which as shown here define the opening 5 and the opening 12 in the 45 respective end plates. The spirals begin at equally spaced points on the periphery of these circles and are carried out to the periphery 35 and 36 of the plates 2 and 9 respectively. It can thus be seen that a maximum number of retaining members for films with a maximum length 50 may be formed in the minimum of space with the greatest possible distance between the films in comparison with the space occupied by the entire cut film holder.

55 As shown in Figs. 1 and 2, the spiral channel guides 3 and similarly 10 are so formed that they terminate at their outer end, intermediate the posts 6. These channel members are designed to guide a film 19 when being loaded in the cut film holder 1. By having the channels 3 and 10 with their walls 37 and 38 respectively terminate intermediate the posts 6, the film will be prevented from contacting the posts. The other end of the channels 3 and 10 preferably terminate with 60 abutments 39 and 40 respectively, thus preventing the film 19 from entering the openings 5 and 12.

The spiral guides 7 as is shown in Figs. 5 and 6 are either projected outwardly from equally 70 spaced points on the peripheries of the inner or outer circles defining the openings 5 and 12 in the end plates 2 and 9 or inwardly from the peripheries 35 and 36 of the end plates 2 and 9 respectively and have a different point of projection but a similar curvature to the spirals 3

and 10 and thus by the cooperation of the channel guides 3 and 10 with the guide members 7, the film is so flexed that its face is kept from contacting the guide members 7 except along its leading edge and at the same time is prevented 5 from buckling.

This cut film holder may be used in any type of developing tank but is particularly adapted for use in a tank of the type shown herein which is disclosed in my Letters Patent No. 2,073,978, 10 issued March 16, 1937.

Such a tank 21 comprises generally a bottom 22, main body portion sides 23, a terraciform detachable cover 24 having shoulders 25 and 27 thereon and an opening 29 therein having an 15 annulus 30 thereabout with a plate 21 subjacent the cover 24 and extending substantially to the periphery of the cover and disposed at a slight distance from the cover. Mounted on the plate 21 in such position as to extend substantially 20 across the opening 29 within the annulus 30 may be a dividing wall 32. A closure member 41 may be provided for the opening 29. Thus when the cover 24 is placed on the tank 21 light will be excluded from the tank. 25

In operation the cut film holder is preferably loaded in a dark room. A film 19 is inserted within the channel guide members 3 and 10. As the film is pushed forward the entering edge thereof will tend to buckle and will thus strike 30 an intermediate guide member 7 which will prevent further buckling. The guide members 7 are preferably so designed that they lie between a projection of the guide members 3 and 10. Thus the film will be prevented from buckling and 35 only the entering edge of the film will contact these guides.

The film 19 is pushed forward until it is substantially within the area of the cut film holder 1 and the process repeated until all of the films 40 to be developed are inserted in the cut film holder or the cut film holder is fully loaded. It can thus be seen that, because of the shape of the channel guide members 3 and 10 which are projected one on the other and are shallow, no portion of the 45 film bearing the image will come in contact with or rub against portions of the film holder. After the film has been inserted in the film holder in a dark room the film holder may be loaded into the tank 21 and the cover 24 placed thereon. After 50 the cover has been placed on the tank the remainder of the developing, fixing and washing of the film may be carried out in the light.

After the film has been developed, fixed and 55 washed the film holder may be removed from the tank and the films taken out of the film holder for printing.

Thus, I have provided a film holder which will 60 carry out a new principle in developing films. This feature being the placing of a plurality of photographic negatives in such a position that each forms a part of a spiral, with the corresponding ends of the negatives adjacent each other. In this manner the negatives form a 65 series of spirals, emanating from substantially the same point. The negatives are spaced apart, permitting circulation of various liquors. In addition, because the negatives are bent to form portions of spirals emanating from substantially 70 common points and projected in the same direction, a minimum amount of space is occupied, or conversely a maximum number of spaced negatives are included in a given amount of space, with the minimum area in contact with a sup- 75

port and the maximum area exposable to developing liquors.

While I have described the film holder as being particularly adapted to be used in conjunction with a tank 21, it may be used in any tank or manner known to the art. To this end I have provided plates 2 and 9. If it is desired, the film holder may be placed on a rod and placed in a tank such as is customary in the art.

Whether the cut film holder is used with an individual, specially adapted tank or in other tanks, it is obvious that I have provided by this construction a cut film holder which is compact, simple in construction and very easily loaded.

While certain novel features of the invention have been disclosed and are pointed out in the annexed claims, it will be understood that various omissions, substitutions and changes may be made by those skilled in the art without departing from the spirit of the invention.

What is claimed is:

1. A cut film holder for developing photographic film, comprising end plates, members connecting said end plates, guide members on the opposing faces of said end plates, additional guide members intermediate said end plates affixed to said connecting members, said first guide members comprising superposed spirals adapted to guide photographic film when inserted in said guide members to form parts of spirals with said films engaged only along their horizontal edges by said first guide members and touching said second guide members adjacent the leading edge of each film.

2. A cut film holder for holding cut photographic films comprising a plurality of spirally shaped U channels mounted in two different and superposed planes, members connecting the U shaped channel members in one plane to the members in the other plane and in opposition thereto, additional guide members intermediate said first guide member, said first guide members adapted to engage the longitudinal edges of films when inserted in said filmholder and said

intermediate guide members adapted to engage a vertical edge of said film.

3. A cut film holder comprising a plurality of aligned arcuate guides disposed in two planes, the guides in one plane facing the guides in the other, members connecting said guides, said guides forming channels for holding the top and bottom edges of photographic films, members connecting said guide and an intermediate guide disposed slightly out of alignment with said first guides and engageable with a third edge of said film.

4. A film holder for developing photographic films, comprising spaced, juxtaposed, perforate end plates, members adjustably connecting said end plates, spiral guide members attached to said connecting members intermediate their ends, additional spiral guide members on opposing faces of said end plates, said guide members on said end plates being in substantial registry with each other and out of registry with said intermediate guide members, one of said end plates being fixedly attached to said connecting members, the second of said end plates being movable on said connecting members toward and away from said other end plate, and means on said second end plate for releasably engaging at least one of said connecting members.

5. A cut film holder comprising a plurality of frame members, arcuate guides thereon, means connecting said frame members in substantially paralleled relation, the distance between said frame members being adjustable by relative movement of said frame members on the connecting members, said frame members and said arcuate guide members adapted to support cut films in arcuate condition, additional guide members intermediate the said first main guides and having a different curvature therefrom whereby they will engage the leading edge only of said cut films for guiding said films into said film holder.

HINSDALE SMITH, JR.
